UNITED STATES PATENT OFFICE.

FLORENCIO COMAMALA UCAR, OF MADRID, SPAIN.

PROCESS FOR ATOMIZING METALS IN A STATE OF FUSION.

1,245,536.

Specification of Letters Patent.

Patented Nov. 6, 1917.

Application filed July 6, 1915. Serial No. 38,362.

To all whom it may concern:

Be it known that I, FLORENCIO COMAMALA UCAR, a subject of the King of Spain, residing at 9 Rue Libertad, Madrid, in the 5 Kingdom of Spain, have invented a certain new and useful Process for Atomizing Metals in a State of Fusion, of which the following is a specification.

It is known that if in the formation of a 10 voltaic arc one or more metal electrodes are employed, these metal electrodes become fused in the zones between which the arc passes; among other applications, the various methods of electric welding are based 15 upon this fact.

On the other hand, if a liquid body is acted upon by a gaseous current that is capable of carrying it along with it, this 20 body is divided into particles of a greater or less degree of tenuity in accordance with the fluidity of the body and the violence of the gaseous current.

Given these facts, if a voltaic arc has 25 been established between two electrodes at least one of which is metallic and a non-oxidizing gaseous current be caused to impinge upon the metallic electrode, the portion of this electrode which had fused is carried along and atomized and can be directed 30 against a body upon whose surface it will form a metallic film whose quality and degree of adherence will vary in accordance with the condition of this surface.

One of the objects of the invention is to 35 improve such a process for the production of metallic films with reference to the action of the non-oxidizing gaseous current.

According to the invention the current 40 of non-oxidizing gas is directed upon the electrode or electrodes in such manner that while passing over or impinging upon the electrode or electrodes, it does not reach the arc which is formed without preliminary contact of the electrodes.

Figure 1 of the accompanying drawings 45 shows in front elevation, by way of example, an arrangement for carrying the invention into practice.

Fig. 2 is a corresponding side elevation.

Figs. 3 and 4 are front and side elevations 50 of another arrangement embodying the invention, and,

Figs. 5 and 6 are front and side elevations 55 of a third arrangement.

In order that the arc may be maintained

notwithstanding the wear of the electrodes, it is sufficient to feed them by employing any appropriate mechanism for this purpose. In order that the arc may be formed and maintained notwithstanding the gaseous 60 current which serves for atomizing the portion that has been fused, the following arrangements may be adopted.

Referring to Figs. 1 and 2, E is an electrode of metal or other conducting substance whose atomization is not material to the carrying out of the invention and which consequently may present such dimensions and effect such movements and which may also be cooled in such a manner that its 70 fusion or volatilization is *nil* or inappreciable for practical purposes. a is the metallic electrode that it is desired to fuse and atomize and which is generally constituted by wires in order to effect its fusion more 75 readily with currents of relatively weak intensity; this electrode is fed in the direction indicated by the arrow f in proportion as it wears. b, b are two twyers discharging the gaseous currents serving to atomize 80 the metal in a state of fusion; these twyers are arranged in such a manner that the gaseous currents they discharge merely pass along the conductor a without impinging against the voltaic arc itself, in order not to extinguish it. In the first place, however, it is necessary to provide for the striking of the voltaic arc between the electrodes E and a, which never contact; moreover, for the continuity and the uniformity of the 90 operation, it is essential that the voltaic arc should be again struck automatically if it should be extinguished as a result of eddies or rushes of gas which might form or as a result of any other disturbing cause. For 95 this purpose the method may be employed which forms the subject matter for another application for Patent No. 38363—dated the 6th July 1915 covering a method of forming a voltaic arc between electrodes that are 100 not in contact, in maintaining the auxiliary current which causes the arc to be struck during the entire time that the atomization of the electrodes a is to continue.

The same process is generalized in the 105 following manner as represented in Figs. 3 and 4.

Referring to these figures, the two electrodes a, a₁ are caused to advance in converging lines; before contact is produced 110

between these electrodes, the voltaic arc is struck by the special method forming the subject matter of another application for patent already referred to and covering a 5 method of forming a voltaic arc between electrodes not in contact; the gaseous currents which issue from the twyers b, b, b, b , impinge against the electrodes and produce the atomization of the portion of these elec- 10 trodes that has fused and the metal thus atomized can be projected against any body of any kind upon whose surface it will form a metallic film of a quality and degree of adhesion varying with the condition of this 15 surface. In order to prevent the possibility of contact between the electrodes a, a_1 in the arrangement illustrated in Figs. 3 and 4, the electrodes may be arranged along intersecting lines as indicated in Figs. 5 and 20 6 with the gaseous jets impinging against each electrode arranged in the manner diagrammatically represented in Figs. 3 and 4 for each electrode.

I claim:—

25 1. A process for atomizing metals in a state of fusion and projecting them on to a surface for the purpose of forming adherent or detachable metallic films, in which an arc is produced between two electrodes one at 30 least of which is formed of the metal which is to be atomized and a blast is caused to atomize the fused metal, consisting in directing gaseous currents upon the electrode or electrodes that are to be atomized so as 35 to pass over or impinge against the said elec-

trode or electrodes and so as not to reach the arc, substantially as described.

2. A process for atomizing metals in a state of fusion and projecting them on to a surface for the purpose of forming adherent or detachable metallic films, in which an arc is produced between two electrodes one at 40 least of which is formed of the metal which is to be atomized and in which a blast is caused to atomize the fused metal, consisting in directing gaseous currents upon the electrode or electrodes that are to be atomized on each side thereof, so as to pass over or to impinge against the said electrode or electrodes and so as not to reach the arc, sub- 45 stantially as described.

3. A process for atomizing metals in a state of fusion and projecting them on to a surface for the purpose of forming adherent or detachable metallic films, in which an arc is produced between two electrodes one at least of which is formed of the metal which is to be atomized and in which a blast is used to atomize the fused metal, consisting in arranging the electrodes out of alignment and in directing gaseous currents on each side of the electrode or electrodes that are to be atomized so as to pass over or to impinge against the said electrode or electrodes and so as not to reach the arc, sub- 50 stantially as described.
